MANUFACTURE OF UNCHILLED METALLIC CASTINGS BY THE CENTRIFUGAL CASTING PROCESS

William Ridley, Beeston, Nottingham, and Percy Hutchinson Wilson, Nottingham, England

Application October 19, 1935, Serial No. 45,814
In Great Britain June 19, 1935

7 Claims. (Cl. 22—65)

This invention relates to the manufacture of unchilled metallic castings by the centrifugal casting process wherein use is made of dry pulverulent materials which are introduced into the mould just prior to the introduction of the molten metal so as to produce a film or lining on the interior surface of the mould for the purpose of preventing the chilling of the casting therein.

Various powdered materials have been employed to that end and satisfactory results are known to have been obtained particularly by the use of ferrosilicon or aluminium or a substance including aluminium in metallic form.

The introduction of the powdered material into the mould has also been practised in various ways including among others a method of blowing the powdered material against the mould interior with the aid of compressed air or feeding it into the mould by means of a feed worm operating within a receptacle surrounding the casting trough. The main effort connected with all known methods so far in use has been directed to the provision of means enabling the film or lining produced within the mould to be uniform and reliable in every respect, failing which faulty castings and considerable waste have been found to result.

In order to attain this object use is made in accordance with this invention of a spiral conveyor or feed worm coupled with means adapted to ensure automatic supply thereto of the powdered material employed for successive casts in definitely reliable and arbitrarily variable quantities and to maintain the feed of the powdered material thereto from the supply tank or feed box constant in every respect.

To this end the spiral conveyor adapted to be driven preferably from a separate motor at variable speeds is fed from a supply tank or box which is so associated with the driving means that in the actuation of the spiral conveyor a certain amount of independent or shaking movement is also imparted or transmitted to the feed box which in turn is communicated to the powdered material therein. In addition the feed box may be and preferably is provided with internal means arranged with advantage in contact with the spiral conveyor whereby additional liveliness is imparted to the material and adhesion thereof to the walls of the charging box is minimized.

The invention also consists in the improved devices for feeding finely divided material, hereinafter more fully described and set out in the accompanying claims.

Referring now to the drawings:—

Figures 1 and 1a show in longitudinal vertical section (broken in the length for convenience) one construction of pipe casting apparatus with associated coating devices according to the invention; the former figure showing the charging end and the latter figure the remote end. 5

Figure 2 is a section, to a larger scale, of parts located to the left hand end of Figure 1.

Figure 3 is a detail as seen in a section on the line 3—3 of Figure 2.

Figure 4 is a cross-section on the line 4—4 of Figure 2.

Figure 5 is a cross-section through the pouring trough shown in Figure 1, to an enlarged scale. 15

Figures 6 and 7 are under-side plan and cross-sectional views respectively of a nozzle or delivery end.

In carrying the invention into effect in one form, by way of example, the drawings show a 20 practically tested form of this invention applied to a pipe spinning machine. This has a rotating and longitudinally movable mould *a* supplied from a stationary pouring trough *b* and a helical conveyor *c* arranged to revolve inside 25 a tube or conduit *d* preferably of steel taking its supply through cut-away portions from a feed box *e* at the top end of the machine. The tube *d* is suitably arranged within and underneath the cast iron liners *f* fitted within the pouring 30 trough *b* down which the molten metal runs to the mould, and terminates in a perforated or nozzle region.

The feed box *e* is attached flexibly at *g* to a hollow supporting member *h* at the end of the pouring trough, and a bracket *h*₁ also attached at that region is used to support the motor *i* and driving gear *k*. At its opposite end the feed box is supported by means of spring metal strips *l* resting on the cants of a nut *l*₁ forming the attachment of the helical conveyor *c* to the driving shaft *k*₁. Steel balls *l*₂ are embodied in each cant so as to reduce wear at this point. Consequently on rotation of the conveyor a vibratory or shaking movement is transmitted to the feed box thereby ensuring movement of the ferrosilicon or other powder inside the feed box to maintain a constant feed thereof to the conveyor. To the same end spring steel wipers *m* are in addition arranged in close proximity to the side 45 walls *e*₁, *e*₂ of the feed box, the lower extremity preferably of each wiper being fitted with a steel ball *m*₁ or other suitable brushing or wiping body. This body engages with the turns or coils of the conveyor *c* thereby receiving and imparting also 50 55

to the wipers *m* a reciprocating or swinging motion as the conveyor revolves, the effect of which motion is to cut the film of the powder tending to adhere to the walls of the box and facilitate 5 its falling down on to the spiral conveyor.

Unlike most spiral or helical conveyors, the one proposed for use here has preferably no central core but consists merely of a stiff helical spring; as an example, to the following dimensions— $\frac{5}{8}$ " outside diameter, $\frac{1}{8}$ " pitch, and constructed of $\frac{3}{16}$ " square wire. This size, however, would obviously be varied for different sizes of apparatus.

The feed speed of the conveyor may be varied 15 as may be required through suitable reduction gearing, a rheostat or other control being to that end incorporated with the motor to vary the speed of the latter.

In operation, molten metal is poured more or 20 less in the usual manner from a tilting ladle *n* down a fall spout *o* and along the pouring trough *b* for delivery over its end *b*₁ on to the mould interior. As soon as the molten metal reaches the delivery end of the trough or in any other 25 suitably timed relationship the motor *i* is started up at the requisite speed causing the conveyor *c* to revolve and deliver the ferrosilicon or other powder along the tube and deposit said powder through holes *d*₁ at the delivery end or nozzle 30 of the tube on to the interior of the mould preferably immediately in advance of the deposition of the molten metal on the said mould. According to demand and the speed imparted to the helical conveyor a corresponding variation 35 in the quantity of ferrosilicon or other powder may be delivered through the perforations or outlets of the tube at the casting end of the trough. With advantage the feed box is provided with a perforated grid *e*₃ at the top to 40 prevent ingress of foreign material.

During working conditions, it is sometimes found necessary to re-set the trough down which the molten metal flows and for this reason the powder supply apparatus is by preference attached as shown directly to the cast iron trunnion arrangement *p* forming or associated with the fixed end *b*₂ of the pouring trough, so that the trough together with the powder supply apparatus is adjusted as found necessary as one 45 unit, and individual settings become unnecessary.

To protect the apparatus during casting operations the motor and feed box may be suitably housed in any desired manner.

The foregoing description refers to apparatus 55 essentially suitable for that method of working in which the pouring in of the metal occurs immediately after the coating of a portion of mould with the powdered material; in other words, the spiral laying of material and of molten 60 metal follow immediately one after the other. Naturally the invention is not limited to this specific method but can also be practised otherwise, e. g. in connection with the dump-trough charging method, the coating being laid in some 65 such cases during the positioning of the charging trough in the mould prior to the dumping of the charge.

Having now described our invention, what we 70 claim as new and desire to secure by Letters Patent is:—

1. A powder distributor comprising a tubular conduit extending along a metal pouring trough and contained within the body thereof, said conduit having a perforated end portion exposed 75 in proximity to the pouring end of the trough,

means for introducing powdered material into its opposite end, a rotatable coreless helical coil member for feeding said material along said conduit to said perforated end, and means for rotating said coil member.

2. A feeding device for finely divided material, comprising a container having downwardly convergent lateral walls, Archimedean screw means passing through said container between the proximate base regions of said walls, a conduit 10 embracing said screw means and extending from opposite ends of said container, and dependent agitator elements secured inside said container and having a wiping action upon said walls and having free extremities resiliently contacting 15 with said screw means.

3. In a pipe casting machine comprising a rotatable mould and a runner trough adapted to deliver molten metal progressively into the rotating mould, the combination therewith of a 20 container for finely divided mould coating material, a conduit from said container secured to and supported by the trough so as to be relatively longitudinally movable with respect to the mould to the same extent as is the trough, a 25 delivery nozzle to said conduit for said finely divided material so located with respect to the delivery end of the trough and the inner surface of the mould as to discharge the material on to those portions of the mould which by the 30 rotating movement of the mould and the simultaneous relative retraction of the trough are, shortly after the application of the coating material, contacted by the molten metal issuing from the trough, a rotatable coreless helical coil 35 screw extending along said conduit from the interior of said container to the region of said nozzle, for delivery of the material thereto, and agitational means at the outer region of said conduit for ensuring flow of the material there- 40 into.

4. Apparatus according to claim 3 comprising means for driving said screw, vibratory means rotatable with said driving means and wherein said container is attached through flexible means 45 to said trough, and means are provided operatively connecting said vibratory means with said container.

5. Apparatus according to claim 3, wherein said screw extends through the base of said container and dependent flexible members are provided within said container attached at upper 50 ends to upper regions of said container and co-operating at their free extremities with the coils of said screw.

6. Apparatus according to claim 3 comprising means for driving said screw wherein said conduit and screw extend together through said container, said driving means being coupled to the screw externally of said container through rotational means adapted to agitate said container by engagement intermittently with means connected thereto.

7. Apparatus according to claim 3, wherein 65 said conduit extends through said container near its base with lateral openings admitting said material to said screw, and comprising spring wipers anchored within said container and brushing the lateral walls thereof, said wipers comprising lower free extremities co-operating with the said screw through said lateral openings.
